UNITED STATES PATENT OFFICE.

ARTHUR M. MULLINIX, OF MARSHALLTOWN, IOWA.

ATTACHMENT FOR CABLEWAY-DUMPS.

SPECIFICATION forming part of Letters Patent No. 546,074, dated September 10, 1895.

Application filed April 10, 1895. Serial No. 545,139. (No model.)

To all whom it may concern:

Be it known that I, ARTHUR M. MULLINIX, a citizen of the United States, residing at Marshalltown, in the county of Marshall and State of Iowa, have invented certain new and useful Improvements in an Attachment for Cableway-Dumps; and I do hereby declare the following to be a full, clear, and exact description of the invention, such as will enable others skilled in the art to which it appertains to make and use the same.

This invention relates to improvements in that class of cableways or rope conveyers employed in removing the earth in excavating for canals, roadways, and work of a like character, and has for its object to provide an attachment for dumping the "skip," no matter in what direction, it may be traveling—that is, away, from or toward the point where the operating power is located—so that the excavated material may be deposited on either side of the excavation without the necessity of changing the position of the tower-supports.

This invention has for its object more especially to provide a device by means of which the skip or load may be dumped on its outward movement—that is, when traveling away from the head-tower and the material deposited on the opposite side of the cut where the tail-tower is located.

The present arrangement to which this improvement pertains only provides for discharging the load on one side of the cut—that is, when the skip is traveling inwardly toward the hoisting-engine or head-tower. The character of the work and the lay of the land often require that the excavated material shall be deposited on the opposite side of the cut from the head-tower.

In the drawings, Figure 1 is an elevation and diagram of a cableway, showing improvised tower-supports, the run of the cables, and the relative position of the hoisting-engine; Fig. 2, a plan and part section of the hoisting mechanism on line 2, Fig. 1, looking in the direction indicated by the arrow; Fig. 3, an elevation of a frame supporting a part of the shifting and dumping mechanism; Fig. 4, an elevation and part section of a power-house, showing the hoisting mechanism; Fig. 5, a broken-away horizontal section on line 5, Fig. 2; Figs. 6 and 7, broken-away details;

Fig. 8, a horizontal section on line 8, Fig. 4; and Fig. 9, an elevation of a tripping-carriage.

A may represent the head-tower, A' the tail-tower, A² the main or stationary cable connecting the two, and which supports the traveling carriage A³, from which the skip A⁴ is suspended.

The engines and operating-drum shown in Fig. 2 are the same as those in ordinary use, with the addition of the improved features.

As will be observed, the drum is of a sectional character, consisting of three parts. The central part B is rigidly mounted on the drum-shaft B' and is provided with a gear-wheel B², with which a pinion B³, mounted on driving-shaft B⁴, engages. By this means the required motion is transmitted to the central or driving part of the drum. The hoisting and dumping part C of the drum is loosely mounted and carries the hoisting-cable C' and the dumping-cable C². These two parts of the drum are adapted to have a frictional clutch-contact, as at a, the joining surfaces being beveled, as shown, and forming the usual conical clutch and imparting the required rotary motion to the drum-part C, which is thrown into and out of engagement by a lever C³. The drum part D carries the endless cable D' and has the same frictional clutch engagement with the driving part of the drum as the part carrying the hoisting-cable, as shown at a'. This part is thrown into and out of engagement by a lever D². The drum part C is provided with an enlarged drum part E, which is of a greater diameter than the hoisting and dumping surfaces. The flanged edge a² of the part E is cut out at one point to provide a recess a³.

The foregoing description relates to the ordinary operating-drum arrangement, the improved attachment being next described.

A bolt a⁴, Fig. 5, is inserted in the drum part E, the outer projecting head end terminating in a hook a⁵, Figs. 2 and 5. To a part of a platform F, on which the operator stands, is pivoted the lower end of a lever a⁶, as at a⁷. The upper end of this lever is forked or bifurcated, as shown in Fig. 7, and bowed inwardly in the direction of the drum, as at a⁸, Fig. 5. An operating or hand-shifting lever a⁹ is pivoted, as at a¹⁰, to a part of the platform, the upper loose end extending up-

wardly within convenient reach of the operator. These two levers are connected by a link *b* and are retained in their normal position by a spring *b'*. One end of an auxiliary dump-cable *G* terminates in a loop *b*², Fig. 6, and is loosely retained in position, Fig. 5, against the inner side of the fork end of lever *a*⁶ by an eyebolt *b*³, a stop or button *b*⁴ resting on the eyebolt. The loop *b*² is in line with the hook end of the bolt *a*⁴, and by throwing forward lever *a*⁹ the loop end of the cable is moved forward into the pathway of the hook-bolt, which will then engage therewith. The fork end holds the loop in position and conveniently allows the hook to engage it without engaging the lever. A frame-support is located in advance of the hoisting-engines and drum and consists of a base part *G'* and uprights *H* *H* and *H'*, as shown in Figs. 3, 4, and 8. The cable *G* runs down under a sheave *b*⁵ forward to and under a sheave *b*⁶ and then straight up between the frame-timbers *H* *H* and is secured to the lower end of an eyebolt *b*⁷, Figs. 3 and 9, inserted in the lower end of a vertically-moving tripping-carriage *H*². The guide-bars *b*⁸ *b*⁹ of the carriage engage with the rabbet-grooves *b*⁹ of the frame-uprights and guide the carriage in its up-and-down movement. A spring *d* is coiled on bolt *b*⁷ and serves to ease the action and break the force of the concussion of the drum connection when the opposite end of cable *G* is engaged. A sheave *d'* is loosely mounted on a shaft *d*² in the carriage-frame and is in the pathway of the dumping-cable *C*², bearing on the upper side thereof, as indicated in Fig. 4. The guard *d*³ retains the cable *C*² in its proper position with reference to its sheave. Two friction-rollers *d*⁴ and *d*⁵ are provided with suitable bearings in the supporting-frame on opposite sides and serve to guide and ease the run of the main dumping-cable when drawn down out of its direct path by the downward movement of the tripping-carriage, as indicated in Fig. 1. To the upper end of carriage *H*² is connected one end of weight-cable *d*⁶, which runs up over companion-sheaves *d*⁷, journaled in the top of the frame, and then down between the inside frame-timber *H* and the outside one *H'* to a counterweight *d*⁸, suspended therefrom. This weight is guided up and down between said timbers or uprights and may consist of a box of sand, as shown in Fig. 8, or any other suitable arrangement.

55 The connection, arrangement, and operation with reference to the traveling carriage *A*³ and the skip connections are of the usual order and will be readily understood.

Under the ordinary arrangement the cable which controls the dump-block is, as the load is hoisted and while traveling, wound on a drum of the same diameter as the hoisting-drum and is subjected to no strain whatever.

When it is desired to dump the load, the cable of the dump-block is forced over by the operator to engage with the recess in the flange of the drum *E* and the dumping-cable drawn

over and wound on said drum at a higher rate of speed than the hoisting-cable and the rear end of the skip elevated until the load is discharged. This provides, however, for only dumping the load when the skip is traveling toward the head-tower.

The improvement set forth in the present application provides a means for dumping the load when the skip is traveling in the opposite direction—that is, toward the tail-tower—so that the combination of the old and the new features provides for the dumping of the load no matter in which direction the skip may be traveling.

It will be understood that the main dumping-cable *C*² is the one ordinarily used in this class of machines and dumps the load on one side of the excavation only. The auxiliary *G* or additional dump-cable *G* is a part of the improved attachment and affords means whereby the load is dumped on the opposite side of the excavation from that of the dumping-cable *C*², thus providing an apparatus wherein the material excavated may be discharged on either side of the cut at the will of the operator without the necessity of transferring the operating power from one side of the cut to the other. When the auxiliary cable is used, the main cable is made to assume the position shown by the diagram in Fig. 1 and indicated by dotted lines in Fig. 4.

The operation of the improved attachment is as follows: When the load is to be dumped with the skip traveling toward the tail-tower, the operator moves the hand-lever *a*⁹ toward the drums, which imparts a corresponding movement to lever *a*⁶ and brings the loop end of cable *G* into position to be engaged by the hook end of bolt *a*⁴, projecting from the drum *E* and winding said cable thereon, which has the effect of drawing down the tripping-carriage *H*², and with it the dumping-cable, to the position illustrated in Fig. 1, and thus tipping the skip and dumping the load. When the motion of the drum is reversed, the cable *G* unwinds and the tripping-carriage and dumping-cables are automatically returned to their normal position by the counterpoise. Thus the auxiliary attachment is always in position for use without requiring any change or alteration in the usual arrangement for dumping on one side of the excavation.

Having thus described my invention, what I claim as new, and desire to secure by Letters Patent, is—

1. In a cable-way dump, the combination with the enlarged rotatable drum-part, of a bolt inserted therein and presenting a hook projection, a lever, provided with a forked-end and having a suitable pivotal connection, a second or hand-lever, pivotally supported, and a link connecting said levers, whereby a forward movement of the hand-lever brings an object supported by the forked-lever into position to be engaged by the hook-projection on said drum, substantially as described.

2. In a cable-way dump, the combination

- with a hoisting and dumping-drum, having parts of different diameters, the main dumping-cable, an auxiliary dumping-cable, having one end in position to engage with and be coiled on the larger part of said drum, a tripping-carriage, connected to the opposite end of said cable and located in the path of and bearing on the upper side of the main dumping-cable, a frame-support, in which said carriage is adapted to have a vertical movement, and means for returning said carriage to its normal position during the time that the auxiliary cable is being unwound from the drum, substantially as described.
- 5 3. In a cable-way dump, the combination with a main dumping-cable, of an auxiliary dumping-cable, adapted to be wound on the dumping-drum, a tripping-carriage, connected to one end of the auxiliary cable, a frame-support, in which the carriage has a vertical movement, a sheave, mounted in said carriage and having frictional contact with the upper side of the main cable, and a weight-attachment, connected to and automatically returning said carriage to its normal position when the strain of the auxiliary-cable is relaxed, substantially as described.
- 10 4. In a cable-way dump, the combination with a rotatable drum, a hook-bolt projecting therefrom, an auxiliary dumping-cable, having a loop formed on one end thereof, a lever, having a bifurcated end and loosely retaining said loop in place, a hand shifting-lever, connected with the first lever, whereby a forward movement of the hand-lever throws said loop into the path of said hook-bolt to be engaged thereby, substantially as described.
- 15 5. In a cable-way dump, the combination with a rotatable drum, of an auxiliary dumping-cable, having one end in position to be coiled on said drum, a tripping-carriage, an eye-bolt, connecting the opposite end of the auxiliary-cable with said carriage, and a spring coiled on said bolt, substantially as described.
- 20 6. In a cable-way dump, the combination of the main dumping-cable, the auxiliary dumping-cable, the tripping-carriage, the supporting-frame, and the guide-sheaves, mounted on opposite sides of said frame, substantially as described.
- 25 In testimony whereof I affix my signature in presence of two witnesses.

ARTHUR M. MULLINIX.
